(57) CLAIM

The ornamental design for a pet house as shown.

DESCRIPTION

FIG. 1 is a front, left, and top perspective view of a pet house, showing my new design;

FIG. 2 is a rear, right, and bottom elevation view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, left, and top perspective view of a second embodiment of the pet house;

FIG. 10 is rear, right, and bottom perspective view of FIG. 9;

FIG. 11 is a front elevation view of FIG. 9;

FIG. 15 is a rear elevation view of FIG. 9;

FIG. 13 is a left side elevation view of FIG. 9;

FIG. 14 is a right side elevation view of FIG. 9;

FIG. 15 is a top plan view of FIG. 9; and,

FIG. 16 is a bottom plan view of FIG. 9.

The broken lines and the shaded areas bounded by broken lines depict portions of the pet house that form no part of the claimed design.

1 Claim, 16 Drawing Sheets
